UNITED STATES PATENT OFFICE.

ELRA A. YOCUM AND JAMES A. SWIHART, OF LIMA, OHIO.

PUMPING-JACK.

SPECIFICATION forming part of Letters Patent No. 756,766, dated April 5, 1904.

Application filed June 19, 1903. Serial No. 162,291. (No model.)

To all whom it may concern:

Be it known that we, ELRA A. YOCUM and JAMES A. SWIHART, citizens of the United States, residing at Lima, in the county of Allen and State of Ohio, have invented new and useful Improvements in Pumping-Jacks, of which the following is a specification.

Our invention relates to new and useful improvements in pumping-jacks for oil-wells; and its object is to provide a simple and inexpensive device of this character adapted to be readily secured to the casing of the well and having means whereby a direct pull may be exerted upon the polish-rod.

15 A further object is to provide propelling means for the rod which may be operated from a source of power located at any desired distance from the well.

Another object is to employ means of novel construction for securing the polish-rod to the propelling means.

With the above and other objects in view the invention consists in the novel construction and combination of parts hereinafter 25 more fully described and claimed, and illustrated in the accompanying drawings, showing the preferred form of my invention, and in which—

Figure 1 is a front elevation of the jack connected to a well-casing and to the polish-rod therein. Fig. 2 is a side elevation thereof; and Fig. 3 is a section on line 3 3, Fig. 1.

Referring to the figures by numerals of reference, 1 is a well-casing having a collar 2 at its upper end. Blocks 3, having recesses 4 in their inner faces, are arranged at opposite sides of the casing 1 directly below the collar 2, and these blocks are secured together by means of bolts 5 or in any other suitable manner. Extending upward from one of the blocks 3 is a standard 6, having a bracket 7 integral therewith, to the outer end of which is pivoted a toothed segment 8. This segment meshes with a rack 9, having a longitudinally-extending groove 10 in its inner face, within which is arranged the polish-rod 11, which extends into the casing 1. The rack is secured to the rod by means of clamping-blocks 12, which extend thereover and are fastened to the rack by means of clamping-screws 13. A recessed ear

14 is arranged at the upper end of standard 6, and the rack 9 and the polish-rod are slidably mounted within the recess. The ear 14 is in alignment with the pivot of the segment 8 and with the meshing portion of said segment and the rack 9, and it is therefore obvious that this ear will hold the rack against lateral movement when power is applied thereto by the segment. A shackle-rod 15 is arranged within one of a series of apertures 16, formed in the segment 60 8, and this rod is adapted to be connected to a suitable source of power arranged at any desired distance from the pumping-jack. When the shackle-rod is reciprocated, the segment 8 will, as is obvious, be moved back and forth 65 upon its pivot, thereby imparting a reciprocating motion to the polish-rod.

The jack herein described can be readily attached to a well-casing, and the rack can also be quickly adjusted upon the polish-rod by 70 employing the clamping-blocks 12. (Shown and described.) By arranging the shackle-rod in different apertures 16 the stroke of the polish-rod can be regulated.

In the foregoing description we have shown 75 the preferred form of our invention; but we do not limit ourselves thereto, as we are aware that modifications may be made therein without departing from the spirit or sacrificing any of the advantages thereof, and we therefore reserve the right to make such changes as fairly fall within the scope of our invention.

Having thus described the invention, what is claimed as new is—

1. The combination with a well-casing having a collar at its upper end; of blocks secured to the casing and below and abutting against the collar, a standard extending upward from one of the blocks, a bracket extending from the standard, a recessed ear at the upper end of the standard, and polish-rod-operating mechanism mounted upon the bracket and within the ear.

2. The combination with a well-casing; of a standard extending upward therefrom and detachably secured thereto, a bracket extending from the standard, a recessed ear arranged at the upper end of the standard, a rack having a longitudinally-extending groove in its inner face, a polish-rod within the groove and ex- 100

2
tending into the casing, clamping-blocks extending into the casing, clamping-blocks embracing the rod and secured to the rack, a segment pivoted to the bracket and meshing with the rack, the pivotal point of the segment being in alinement with the ear of the standard, and means adjustably connected to and adapted to reciprocate the segment.

In testimony whereof we affix our signatures in presence of two witnesses.

ELRA A. YOCUM.
JAMES A. SWIHART.
